Brook Lefevre

UNITED STATES PATENT OFFICE.

MORRIS HALPERIN, OF BROOKLYN, NEW YORK.

BOAT.

1,287,977.

Specification of Letters Patent. Patented Dec. 17, 1918.

Application filed May 21, 1918. Serial No. 235,826.

To all whom it may concern:

Be it known that I, MORRIS HALPERIN, a citizen of the United States, and resident of the borough of Brooklyn, in the city and State of New York, have invented a new and useful Improvement in Boats, of which the following is a specification.

My invention relates to boats and particularly to small boats to be used as life boats, and has for its object the provision of means for materially reducing the tendency of the boat to capsize when being launched and when afloat in rough water.

A further object is to provide a simple and efficient device for increasing the seaworthiness of a boat, which device can be attached to any boat with very little labor and at small expense.

Another object consists in providing certain improvements in the form, construction and arrangement of the several parts whereby the above named and other objects may be effectively attained.

A practical embodiment of my invention is represented in the accompanying drawings in which,

Figure 1 represents a perspective view of a boat with my stabilizing device in operative position.

Fig. 2 represents an inverted plan view of the same.

Fig. 3 represents a vertical section taken in the plane of the line III—III of Fig. 2.

Fig. 4 represents a detail plan view of a portion of a modified form of stabilizing fin.

Fig. 5 represents a vertical section taken in the plane of the line V—V of Fig. 5.

Fig. 6 represents a view similar to Fig. 2, showing a modified form, and

Fig. 7 represents a vertical section taken in the plane of the line VII—VII of Fig. 6.

Referring to the preferred form shown in Figs. 1 to 3 inclusive; the hull 1 of the boat is provided with a central keel 2 to which laterally extending fins 3 are attached by means of lag screws, bolts, or in any other convenient manner.

The fins 3 may be formed of sheet metal, as shown in Fig. 1, or they may have a metal frame 4 and a covering 5 of suitable cloth, such as water-proofed duck or canvas, as shown in Figs. 4 and 5, and are preferably made narrow near the keel but greatly widening out toward their ends so as to pro-

vide a considerable bearing surface against the water at these points. The fins, as shown in Fig. 1, are arranged in pairs, one pair forward and one pair aft of the center of the boat, but it will be understood that such a number of pairs of fins may be used as are found desirable or necessary, and they may be formed separately or in a continuous piece.

Vertically extending braces 6 are provided, which are attached to the ends of the fins 3 and to the side rails of the boat, and serve to hold the fins securely in place.

In operation the fins 3, which are located below the water line and spaced from the bottom of the boat, will tend to prevent either side of the boat from rising and the opposite side from lowering, and thus the effect of rough water and sudden shifting of the boat's burden will be materially reduced, the stability of the boat increased and its operation made much easier and safer.

Referring to the modified form shown in Figs. 6 and 7, the fins, denoted by 7, are very much elongated and placed longitudinally of the boat. They are also spaced a considerable distance from the keel 2, to which they may be secured by braces 8, while braces 9, quite similar to the braces 6 of the preferred form, extend from the outer edges of the fins 7 to the sides of the boat.

In regard to both the preferred and modified forms, it will be seen that the fins lie substantially in the plane of the keel of the boat, and that their effective area is spaced from the keel. This last feature is accomplished in the preferred form by the narrowing of the fins as they approach the keel, and in the modified form by actually spacing the fins from the keel. This arrangement is very much more advantageous than one in which the effective area of the fins is immediately adjacent the boat, for the reason that it permits the free passage of water between the effective area of the fins and the hull of the boat. I also find that it is highly desirable to have the fins as low down as the plane of the keel.

It will be understood that various changes may be resorted to in the form, construction, size and location of the fins without departing from the spirit and scope of my invention, and hence I do not intend to be limited

to the details shown and described except as they may be specifically set forth in the claims.

What I claim is:

- 5 1. The combination with the hull of a boat, of a pair of fins spaced from the bottom of the boat and attached to its keel and extending outwardly on opposite sides for maintaining the equilibrium of the boat in the water.
- 10 2. The combination with the hull of a boat, of a pair of fins spaced from the bottom of the boat and attached to its keel and extending outwardly on opposite sides for maintaining the equilibrium of the boat in the water, and vertical braces extending from the said fins to the sides of the boat.
- 15 3. The combination with the hull of a boat, of a pair of fins attached to the keel of the boat and extending laterally therefrom on opposite sides for maintaining the

equilibrium of the boat in the water, said fins being relatively narrow at their point of juncture with the keel and relatively wide at their extremities.

25

4. The combination with the hull of a boat, of a pair of fins attached to the boat and extending laterally therefrom on opposite sides for maintaining the equilibrium of the boat in the water, the effective area of said fins being spaced from the boat.

5. The combination with the hull of a boat, of a pair of fins spaced from the bottom of the boat and attached to its keel and extending outwardly on opposite sides for maintaining the equilibrium of the boat in the water, the effective area of said fins being spaced from the boat.

In testimony, that I claim the foregoing as my invention, I have signed my name, this 17th day of May 1918.

MORRIS HALPERIN.
